UNITED STATES PATENT OFFICE.

MARY A. MARTIN, OF SPRINGFIELD, MASSACHUSETTS.

SEAM FOR WIRE-CLOTH FOR PAPER MANUFACTURE.

SPECIFICATION forming part of Letters Patent No. 258,937, dated June 6, 1882.

Application filed April 14, 1882. (No model.)

To all whom it may concern:

Be it known that I, MARY A. MARTIN, a citizen of the United States, residing at Springfield, in the county of Hampden and State of Massachusetts, have invented a certain new and useful Improvement in Seams for Wire-Cloth for Paper Manufacture, of which the following is a specification, reference being had to the accompanying drawings, forming a part thereof.

Figure 1 is a top view of a section of the wire-cloth cover of a dandy-roll sewed together by the wire B according to my invention. Fig. 2 is an end view of the wire-cloth and seam shown in Fig. 1. Fig. 3 is a top view of a section of the wire-cloth cover sewed together by the wire E in a manner heretofore used. Fig. 4 is an end view of the wire-cloth and seam shown in Fig. 3. Fig. 5 is the dandy-roll, with an enlarged view of the improved seam.

In seams heretofore made the edges of the wire-cloth have been interwoven and the wire strands twisted together under the surface of the cloth; or the edges have been unraveled and the projecting strands bent backward and the seam-thread run around the respective edge-wires, as shown in Fig. 3, leaving an unfilled space in the cloth, and the only force by which the edges were held together and prevented from unraveling being that produced by turning under the wire strands.

In my invention, after first unraveling the edges and bending under and backward the projecting strands, the seam-wire B is carried half-way around the wires F F, on their under side, then up and over the wire I, behind its knuckle on the wire F, and between the wires F and P, then back again half-way around the wires F F, on their under side, up and over and behind the knuckle of the alternate opposite wire I, and so continuously. In my invention the seam-wire B does not run around the wires F F, but is made to run over the wires I, behind the knuckle on the wire F, in order to strengthen the tension of the seam, the seam-wire B, in running half-way around the wires F F and over and behind the knuckle of the wire I, locking together the edges of the cloth.

I claim as my invention—

In a seam for wire-cloth for paper manufacture, the combination of the unraveled and backward-bent strands, and the seam-wire B, carried half-way around the edge-wires F F, and over and behind the knuckle of each alternate opposite wire I, as and for the purpose set forth.

MARY A. MARTIN.
